UNITED STATES PATENT OFFICE.

PEARL J. WENTWORTH, OF FORT THOMAS, KENTUCKY.

PROCESS OF MAKING SHOES.

1,280,604.

Specification of Letters Patent: Patented Oct. 1, 1918.

Application filed November 19, 1917. Serial No. 202,685.

To all whom it may concern:

Be it known that I, PEARL J. WENTWORTH, a citizen of the United States, and residing at Fort Thomas, in the county of Campbell and State of Kentucky, have invented new and useful Improvements in Processes of Making Shoes, of which the following specification is a full disclosure.

My invention deals with the production of a shoe in which many of the operations or steps now prevailing in its manufacture are eliminated, whereby the cost of production is materially lessened, the manufacture simplified, and a product of higher quality and finish corresponding to lines of the last is produced.

One object within the contemplation of the invention is to formulate a sequence of manipulative steps orderly related to one another as well as individually simple and easily accomplished, to the end that the manufacture of the shoe may be cheapened and many machine operations eliminated.

Another object of the invention is to unitarily combine a molded-to-form cut sole, heel and shank stiffener previous to securing the same to the shoe upper.

Another object of the invention relates to lasting the shoe upper and cementing its turned margins to the insole or sock lining.

Another object of the invention is to temporarily secure a unitarily combined molded-to-form outsole and heel in place upon the shoe upper while the upper is lasted and removing the last for permanently stitching and securing the combined sole and heel.

Another object of the invention is to avoid repeated sole tempering operations during the process of shoe manufacture or securing a tempered sole to the upper.

Another object of the invention is to avoid sole leveling, reduce waste of sole leather, and to avoid nails protruding up and through the insole.

Other objects and advantages will be in part disclosed in the annexed drawings and in part indicated in the following description thereof.

In order that the method and product may be so fully revealed as to enable others to practice the same, drawings indicating steps in the process of shoe manufacture have been appended as a part of the disclosure, and in such drawings, like charac-

ters of reference denote corresponding parts throughout the several views, of which:

Figure 1 is a perspective view of a lasted shoe upper in condition to receive the sole.

Fig. 2 is a perspective view of the unit sole, heel and shank stiffener ready to be placed upon the lasted shoe upper.

Fig. 3 is a sectional view of the lasted upper with the unit sole and heel applied showing the method of driving a nail or fastener through the last.

Fig. 4 is a top plan view of a shoe with the upper cut away at the heel portion, illustrating a row of tacks, with their heads upward for securing the heel to the insole and heel seat margin of the upper.

Fig. 5 is a bottom plan view of the shoe, illustrating the line of stitching for securing the sole to the insole and upper.

The invention relates more particularly to a McKay type of shoe, in which the sole is directly secured to the upper and not to a welt, although a welt type of shoe may be included.

While the invention may be characterized as a process or method of making a shoe, various preliminary steps, while essential, need not be defined herein in detail, as they may represent steps as separate and distinct from the invention contemplated herein, and which may be practised independently to produce articles of commerce. Likewise the sequence of steps need not follow the orderly relation as herein presented, nor every step included to make the finished product, as different grades of stock and styles of shoes would necessarily diversify the practice from minor aspects.

Lasting.

The upper 1 is pulled over the last 3 in a customary manner, but preferably upon a last having no metal bottom. As the upper is not tacked, no metal bottom last is required which offers a saving in the cost of the last. After pulling over the upper, the sole and heel margins are stretched, cemented upon the insole and are molded to the shape of the last bottoms. This fits the upper snugly to the last so as to conform exactly to the shape of the last. Wherever required, the upper may be ironed to insure its shaping to the outline of the last. The cement in drying effects a slight shrinkage

of the material over the bottom of the last, drawing the upper more snugly to the last, and when dry results in a permanent set of the insole and margins to the shape of the 5 bottom of the last. The insole and the overlapping margins of the upper may be finished to provide a smooth surface, which adds flexibility to the material and comfort to the wearer of the shoe, very important 10 desiderata in the shoe art. Now, with the shoe upper shaped and perfectly finished to the contour of the last, it will hold its shape permanently in the succeeding steps of applying the sole and heel, because no occasion arises for upsetting its shape in the 15 method of applying such parts, nor is the upper subjected to strains severe enough to destroy its shape.

Unit sole, heel and shank stiffener.

20 In Fig. 2 of the drawings, a unit sole and shank stiffener is shown, which, of itself, is the result of several process steps, and may be treated as an article of commerce or manufacture, separate and distinct from its assembly into a shoe.

25 2 indicates an outersole died or cut to pattern and to exact shoe size and molded to conform to the shape of the bottom of the 30 last, its outer sole surfaces completely conformed to the lines desired for the finished shoe, as rounded, crosswise of the shank, and leveled at the ball and other portions of the sole.

35 35 For a molding process of the sole it is only necessary to slightly moisten or sponge the sole material, preparatory to pressing to shape under a heavy pressure, to prevent the finished surface of the material from checking. 40 The material is not water-soaked to the degree required for tempering under the ordinary methods of shoe making. Such water soaking is very injurious to the leather materials, destroying their wearing qualities and frequently causing water stains.

45 The sole being subjected to a heavy molding pressure retains its shape and being perfectly molded before attaching it to the upper, requires no leveling after it is secured 50 to the upper, thus saving a breaking down of the stitching and shoe as is the case in the leveling process under the established method. The leveling operation is entirely eliminated. The sole representing a product 55 in a shoe finished state is made from a blank considerably reduced in size over a sole blank for a corresponding size of sole finished upon the shoe.

60 No waste allowance for several temperings and trimming is made, thus a saving in material and also of time, as there is no delay or interruption in the manufacture, as permitting the shoe to dry before finishing. After the outsole has been molded, a finished 65 heel 7 is secured to the heel portion thereof,

preferably by a row of tacks 4 extending marginally around the heel and the tacks are driven from the inner face of the sole downwardly or outwardly into the seat or base lift of the heel. The tack heads are 70 adjacent to the insole, leaving no protruding sharp points on the inside of the finished shoe. High French heels may be further secured to the sole by driving a nail 8 centrally through the sole and heel lifts, extending 75 to the top lift of the heel. A finished heel can therefore be firmly and rigidly attached to the outsole, or the heel can be 80 breasted and the top lift attached before the outsole is attached to the upper. This avoids heel building, securing and finishing operations after the sole has been applied to the upper, (thus eliminating several machine operations) and produces a more secure anchoring of the heel to the sole. 85

A shank stiffener 5 may be compressed into the inner face of the outsole at the time of molding or subsequently applied, as shown, by driving a nail 10 through its heel end and into the heel, rigidly fastening the 90 shank stiffener in place, so that it cannot be improperly placed in the shoe or loosened after the sole has been secured to the upper.

95 It will be observed that the heel portion of the sole, as shown in Fig. 2, extends slightly beyond the heel edge or circumference, an allowance made for trimming or finishing at the heel after the sole has been temporarily applied or laid upon the lasted upper. 100

Securing sole unit to upper.

Disregarding the steps or process of manufacture incidental to forming and combining the sole, heel and shank stiffener into a 105 unit and treating the same as components of the sole; then as a second step to the process herein, the unit sole and heel piece is laid upon and cemented to the bottom of the lasted upper. The cement is applied preferably over the entire sole surface so that it is not susceptible to leave hollow portions between the connected parts. 110

115 The heel end of the last, as shown in Fig. 3, has a central angular bore 6 therethrough, providing an opening into which a nail driver, (shown in dotted lines in Fig. 3), may be inserted to drive a nail 9 outwardly through the insole, and into the sole and heel, additionally securing the parts to enable the sole heel edge to be trimmed while 120 the upper is lasted.

125 The last is then removed from the upper and a row of tacks 11 are driven from the inside of the shoe outwardly around the heel seat margin of the upper into the sole and heel. The sole is then stitched to the insole and turned margin of the upper, by a marginal line of straight stitching 12 through said parts, commencing at one edge of the heel 130

breast, running forward to the toe and around the toe rearwardly to the opposite heel breast edge, using an ordinary shoe sewing machine having a horn reaching into the upper. By straight or perpendicular stitching the stitches pass through the outer sole from the outer face of the outer sole and through the inner sole and underlying lap or sole securing margin of the upper 10 along a line formed by the inner loops of the stitches, approximately directly opposite the line formed by the outer loops of the stitches. The stitches pass through the parts at a right angled or perpendicular 15 line to the face of the outer sole, bringing the stitching along a line away from the edge of the sole securing lap of the upper, providing a better anchorage for the stitches.

The sole being cut to shoe finished size 20 and molded to final shape and cross-sectional curvature, has the marginal portion of the sole, especially at the shank, fitting into close proximity to the upper, and the central portion of the sole conforms closely 25 to the shoe bottom and after being stitched permanently holds its shape. The tension of the stitching is not destroyed by any subsequent rounding of the sole, as rounding and leveling operations are eliminated, and, 30 therefore, there is no tendency for the sole to separate from the upper after the shoe is worn.

The stitching may be concealed or exposed 35 at the outer surface of the sole as desired. For concealed stitching a channel or furrow may be formed into the sole as disclosed in an application filed by me on May 24, 1917, Serial No. 170,597, for improvement in shoe soles, and which can be formed 40 at the time of stitching.

It will thus be seen that this invention is well adapted to achieve the ends aforesaid, in a very simple yet expeditious manner and practised quite independently of any new or 45 special type of machines, and is not a mere function of any given machine. It eliminates the use of many machines now required in shoe making. The sole is secured and stitched to the upper in a dry condition 50 so that there is no occasion for it destroying the shape of the upper or marring the finish of the upper. This is of particular advantage in the manufacture of shoes made of delicate shades of upper material, as they 55 are not liable to water staining, occurring from a water-soaked sole under the ordinary processes.

Having described my invention, I claim:

1. A method of making shoes, comprising: 60 cutting an outer sole to shoe finished size and molding to final curvature, lasting a shoe upper with insole, cementing the overlying margins of the upper extending over the bottom of the last to the insole, and se- 65 curing the said molded to finished form

outer sole to the upper by a row of straight stitching, with the last removed.

2. A method of making shoes, comprising cutting an outer sole to shoe finished size and molding to final curvature, lasting a 70 shoe upper, bringing the upper margins over the bottom of the last, then temporarily securing the molded-to-shape sole to the upper, and permanently securing the applied sole by a row of straight stitching with the 75 last removed.

3. A method of making shoes, comprising lasting a shoe upper and insole, drawing the margin of the upper over the bottom of last and insole, cementing the same to the insole, applying a molded-to-form outer sole 80 to the lasted upper, removing the last and stitching the forepart and shank portions of the outsole to the upper and insole, and nailing the said parts at the heel portions 85 from the inside of the upper outward.

4. A method of making shoes, comprising cutting an outer sole to shoe finished size and molding to final curvature, securing the molded-to-shape outer sole temporarily to a 90 lasted upper, removing the last and then stitching the sole to the upper.

5. A method of making shoes comprising securing a unitary outsole and heel temporarily to a lasted upper, the outsole being 95 molded-to-form, removing the last and permanently securing the parts.

6. A method of making shoes, comprising securing a unitary outsole, heel and shank stiffener temporarily to a lasted upper, the 100 outsole being molded-to-form, removing the last and permanently securing the parts.

7. A method of making shoes, comprising lasting a shoe upper with insole, cementing to the insole the margins of the upper extending over the insole at the bottom of the last, temporarily securing a molded-to-form sole having a heel applied thereto to the upper, then removing the last from the upper and permanently securing the said sole 110 to the upper and insole.

8. A method of making shoes, comprising lasting a shoe upper and insole, drawing the margin of the upper over the bottom of last and insole, cementing the same to the 115 insole, cementing a molded-to-form outer sole to the lasted upper, removing the last and stitching the forepart and shank portions of the outsole to the upper and insole and nailing the said parts at the heel portions 120 from the inside of the upper outward.

9. A method of making shoes, comprising cementing to a lasted upper an outsole cut to finished size and molded to final curvature, removing the last and permanently securing the sole to the upper by straight stitching.

10. A method of making shoes comprising cementing a unitary outsole and heel to a lasted upper and insole, the outsole being 130

molded-to-form, nailing said parts at the heel from the inside outwardly, removing the last and permanently securing the parts.

11. A method of making shoes, comprising cementing a unitary outsole, heel and shank stiffener to a lasted upper and insole, the outsole being molded-to-form, nailing said parts at the heel from inside the upper outwardly, removing the last and permanently securing the parts.

12. The method of making shoes, comprising securing a heel and shank stiffener to the outersole of a shoe before the said sole is laid upon a lasted upper, temporarily securing said unitary sole, heel and shank stiffener to the bottom of a lasted upper, removing the last and permanently securing the parts.

13. The method of making shoes comprising molding a sole to its finished shoe shape, securing the same to a lasted upper temporarily by cementing the parts, removing the last and permanently securing said parts by stitching and nailing, the nails being driven from the inside of the upper through the upper margins outward into the sole and heel.

14. The method of making shoes comprising molding a sole to its finished shoe shape, permanently securing a finished heel to the outsole, securing the unitary outersole and heel to a lasted upper temporarily by cementing the parts, removing the last and permanently securing said parts by stitching and nailing, the nails being driven from the inside of the upper through the upper margins outward into the sole and heel.

15. A method of making shoes, comprising cutting an outer sole to shoe finished size and molding to final curvature, lasting a shoe upper and inner sole, cementing the overlying margin of the upper upon the inner sole, cementing the said shaped-to-form outer sole upon the lasted inner sole and upper, removing the last and stitching the outer sole to the upper and inner sole.

In witness whereof, I hereunto subscribe my name, as attested by the two subscribing witnesses.

PEARL J. WENTWORTH.
